HOLDER FOR JEWELRY, EYEGLASSES OR
THE LIKE

George Growe, 7147 Wicker Ave., Hammond, Ind.

Filed Mar. 8, 1960, Ser. No. 59,675

Term of patent 7 years

(Cl. D57—1)

I claim:

The ornamental design for a holder for jewelry, eyeglasses or the like, as shown.
